UNITED STATES PATENT OFFICE.

GEORGE GILCHER, OF RIDGEFIELD PARK, NEW JERSEY.

PILOT-LIGHT.

1,029,805.

Specification of Letters Patent. Patented June 18, 1912.

Application filed July 1, 1909. Serial No. 505,452.

To all whom it may concern:

Be it known that I, GEORGE GILCHER, a citizen of the United States of America, and a resident of Ridgefield Park, New Jersey, have invented a new and useful Improvement 5 in Pilot-Lights, which improvement is fully set forth in the following specification.

My invention relates to "pilot-lights" 10 for gas-cocks.

It is an improvement upon the construction set forth in U. S. Letters-Patent No. 912,304, granted to me Feb. 16, 1909, for a device that may be changed from an ordinary 15 gas-cock to a "pilot-light", and vice versa. The object of the present invention is to improve, simplify and cheapen the construction shown in my previous patent.

The invention will be best understood by 20 reference to the annexed drawings that illustrate a preferred embodiment, of which—

Figure 1 is a side view partly in section; and Fig. 2 is an end view, through line II—II of Fig. 1.

25 In the drawings, 1—1 represents the ordinary gas-pipe, and 2 the barrel or chamber, in which the gas-cock is mounted in the usual manner. This barrel 2 is cut away at 3, and on either side of the cut-away portion is provided with the two oppositely-disposed wings or flanges 4—4, in each of which is mounted an adjustable screw 5.

6 is the gas-cock or stopper that is secured in the barrel 2 in the usual manner, 35 and its interior construction being of the usual type need not be shown. Transversely through the body portion of this cock is the (diagonal) slot 7, which is more or less elongated in the direction of the 40 axis of the cock. From the side of the stopper 6 that is opposite the cut-away portion 3, from either side of the lower end of slot 7 (which is farthest from the cut-away portion 3) are the two projections 8 that 45 furnish a bearing in which is pivoted, at 9, a transverse lever. One end 10 of this lever serves as a handle or thumb-piece, and the other end protrudes through the slot 7 to present the nose 11 for limiting the axial 50 turning of the cock. Sufficient tension or friction is applied upon the pivot 9 (as by a clamp-nut or the like) to cause the lever to remain in whatever position it may be placed.

55 The location and arrangement of the transverse slot 7 and its lever with relation

to the wings 4 and set-screws 5 is such that when the nose 11 of the lever is in its lowermost position, as shown in Fig. 1, it will not be in line with the set-screws 5 but (when cock 6 is turned) will pass beneath the same and abut against one of the shoulders 4; whereas, when the nose 11 is in its uppermost position, as indicated in Fig. 2, it will abut against one of the set-screws 5. 60 65

In Fig. 1 the device will operate as an ordinary gas-cock; and by bringing the device into the position shown in Fig. 2, it acts as a pilot-light. By turning the screws 5, in or out, the amount of play permitted 70 the cock 6 is varied, and the size of the pilot-light varied accordingly. In fact, the two screws may be adjusted to different lengths, so that if the cock is turned in one direction, a certain amount of gas will pass, while 75 when the cock is turned in the other direction more gas (or less gas) can pass. This provides simultaneous variations for two different sized pilot-lights. But it is obvious that the set screws may be dispensed 80 with entirely, in which case their place is taken by any projection that would limit the play of the nose 11 when in its upper position; or the barrel 2 with its flange 4 will be so shaped, as by giving an inclined 85 face to the latter, as to produce the same effect.

Having thus described my invention, I claim:

1. The combination of a gas-fixture, a gas-cock turning axially therein, a pivotally-adjustable stop carried by said cock, a stationary stop on said fixture and located in the path of said stop in only one of the adjustments thereof, and a second stationary 95 stop on said fixture and located out of the path of said stop in its first-named adjustment and in its path in the second adjustment thereof.

2. A gas-fixture comprising a stationary 100 barrel having a wing with a set-screw therein, a gas-cock mounted to turn axially in said barrel and having a transverse slot, and a lever protruding from said slot and adjustable to abut against either the wing 105 or the set-screw.

3. A gas-fixture comprising the hollow barrel having a cut-away portion between two radial wings, a set-screw projecting through each wing toward said cut-away 110 portion, a gas-cock located in said barrel and having a transverse slot therethrough

with projections on either side of one end of said slot, and a lever pivoted between said projections and protruding through said slot for engagement at will either with one of said wings or one of said set-screws.

4. The combination with a gas-fixture, of a pair of oppositely-disposed and relatively-stationary stops, a second pair of oppositely-disposed and relatively-stationary stops, and 10 a relatively movable stop that is adjustable to co-act at will with either member of one pair only of said stationary stops to the exclusion of possible engagement with either member of the other pair, and vice versa.

5. The combination, in a gas-fixture, of 15 a barrel having a wing with a set-screw therein, a gas-cock turning axially in said barrel, and a stop carried by said cock that is adjustable to co-act with the wing to the exclusion of the set-screw and vice versa. 20

In testimony whereof I have signed this specification in the presence of two subscribing witnesses.

GEORGE GILCHER.
